US0D1110821S

(12) **United States Design Patent** (10) Patent No.: **US D1,110,821 S**
(45) Date of Patent: ** Feb. 3, 2026

(54) **TROWEL FOR SPREADING PUTTY**

(71) Applicant: **PECTRO, S.L.**, Ribarroja del Turia
(ES)

(72) Inventor: **Gabriel Guillem Criado**, Valencia (ES)

(**) Term: **15 Years**

(21) Appl. No.: **35/521,182**

(22) Filed: **May 13, 2024**

(80) **Hague Agreement Data**

Int. Filing Date: **May 13, 2024**

Int. Reg. No.: **DM/237381**

Int. Reg. Date: **May 13, 2024**

Int. Reg. Pub. Date: **Jun. 7, 2024**

(51) **LOC (15) Cl.** **08-05**

Primary Examiner — George J Ulsh

(57) **CLAIM**

The ornamental design for a trowel for spreading putty as shown and described.

DESCRIPTION

1. Trowel for spreading putty

1.1: Perspective

1.2: Front

1.3: Top

1.4: Right

1.5: Rear

1.6: Bottom

1.7: Left

Figure 1.1 is a front perspective view of a trowel for spreading putty showing my new design; Figure 1.2 is a front elevational view thereof; Figure 1.3 is a top plan view thereof; Figure 1.4 is a right side elevational view thereof; Figure 1.5 is a rear elevational view thereof; Figure 1.6 is a bottom plan view thereof; and Figure 1.7 is a left side elevational view thereof.

1 Claim, 7 Drawing Sheets
